(57) **CLAIM**

What is claimed is the ornamental design for a steel stud deflection connector, as shown and described.

DESCRIPTION

FIG. 1 is a perspective view of a first embodiment of a steel stud deflection connector, showing the new design;

FIG. 2 is a front elevational view thereof;

FIG. 3 is a left-side elevational view thereof;

FIG. 4 is a rear elevational view thereof;

FIG. 5 is a right-side elevational view thereof;

FIG. 6 is a top plan view thereof, the bottom plan view being a mirror image thereof;

FIG. 7 is an environmental perspective view, illustrating the first embodiment of the design positioned as though in use;

FIG. 8 is a perspective view of a second embodiment of the design;

FIG. 9 is a front elevational view thereof;

FIG. 10 is a left-side elevational view thereof;

FIG. 11 is a rear elevational view thereof;

FIG. 12 is a right-side elevational view thereof;

FIG. 13 is a top plan view thereof, the bottom plan view being a mirror image thereof; and,

FIG. 14 is an environmental perspective view, illustrating the second embodiment of the design positioned as though in use. The broken lines showing building frame elements in FIGS. 7 and 14 are included for the purpose of illustrating the invention in use, and form no part of the claimed design.
